UNITED STATES PATENT OFFICE.

EDWARD HANAK, OF NEW ORLEANS, LOUISIANA.

PORTABLE STACKING-ELEVATOR.

No. 897,462.

Specification of Letters Patent.

Patented Sept. 1, 1908.

Application filed September 28, 1906. Serial No. 336,295.

To all whom it may concern:

Be it known that I, EDWARD HANAK, residing at New Orleans, in the parish of Orleans and State of Louisiana, have invented 5 a new and Improved Portable Stacking-Elevator, of which the following is a specification.

This invention, which generally relates to improvements in portable elevators, seeks to 10 provide an improved construction of elevator of the type referred to, more especially adapted for use in ware houses, for elevating and storing sugar, rice, cotton-seed meal and other commodities, in sacks, barrels or pack- 15 ages, which can be readily moved to any part of the ware house at will, and which can be quickly adjusted for delivering goods to the desired place or places.

In its generic nature, my invention comprehends an improved construction of elevator, in which is included a hinged and adjustable frame section for sustaining the endless carrier frame at different vertical planes and capable of being gradually extended or 25 shortened relatively to the different varying vertical adjustments of the carrier frame.

In its more complete nature, my invention embodies a hinged carrier frame, adapted to be swung to different vertical planes, a fold- 30 able frame section for supporting the upper or delivery end of the carrier frame, and cer- 35 tain details of construction and peculiar combination of parts, all of which will be herein- after fully described, specifically set out in the appended claims and illustrated in the accompanying drawings, in which:—

Figure 1, is a side elevation of the form of machine shown in Fig. 2, parts thereof being in section, and the carrier frame and the ex- 40 tensible supporting frame being shown in the depressed position in dotted lines. Fig. 2, is a front elevation of the machine. Fig. 3, is a detail perspective view of one of the telescopic supporting frame members and the 45 means for extending the same. Fig. 4, is a perspective view of a modified construction of my invention which will hereinafter be referred to. Fig. 5, is a view of a further modification thereof, also hereinafter ex- 50 plained. Fig. 6, is an enlarged detail section taken on the line 6—6 of Fig. 2.

In the preferred construction of my invention and as illustrated in Figs. 1 to 5, the same comprises a base or main frame formed 55 of the horizontal and longitudinally disposed beams 1—1, and a rear cross beam 2, said base

frame being mounted on a pair of front and rear caster rollers 3—3, as shown. The base frame also includes supplemental horizontal timbers 10—10 that are braced to the side and 60 end beams 1 and 2, which latter, together with the timbers 10—10 form the support for the driving mechanism, which, as shown, is in the nature of an electric motor 5, whose driving belt 6 takes around a drive pulley 7, 65 mounted on a shaft 8, transversely journaled in suitable bearings 9—9 on the side beams 11—11 near the lower ends thereof, as clearly shown in Fig. 1.

The carrier frame is pivotally mounted at 70 its lower end upon a cross shaft *a* journaled at the opposite ends in bearing boxes *b* se- 75 cured upon the under side of the side beams 1—1, see Fig. 1, by reference to which and to Fig. 2 it will be also noticed that the said 75 shaft *a* carries a pulley 12, over which takes an endless carrier belt 13 which also passes over the pulley 14 on the shaft 14^a, adjust- 80 ably mounted on slotted brackets 15—15 se- cured on the upper ends of the side beams 80 11—11 in which the journal boxes 16—16 for the shaft 14^a are slidably held by means of adjusting screws 17—17, as shown. The carrier belt 13 has transverse cleats that 85 form lifting members 13^a and it also has its upper portion held to travel over the hori- 90 zontal guide rollers 18, transversely mounted on the side beams 11.

Motion is imparted to the endless belt 13 by means of a pinion 19 on the drive shaft 8 90 that meshes with a gear 19^a on a counter- shaft 20 journaled in bearings 21 on the side beams 11 and which, at one end has a sprocket wheel 21^a around which takes an 95 endless sprocket chain 22 which passes over the large sprocket wheel 23 on the corre- 100 sponding end of the shaft 14^a, which trans- mits motion to the endless carrier, and to take up unnecessary flexure of the chain 22 it is passed over a tightener or side pulley 24 100 on the guide beam, as shown.

25—25 designate outwardly inclined guard bars that are mounted on the upper edge of the side beams 11.

To provide a simple and convenient means 105 for supporting the upper end of the carrier frame with its upper face clear of obstruc- tions and for raising or lowering the said frame as conditions may require, I use a hinged extensible frame which consists of two 110 opposing side supports, which consist of a pair of telescopically connected members,

the lower ends 26 of which have T-shaped ribs 27 on their inner faces, on which slide the T-shaped guide flanges 28 formed on the outer faces of the upper telescopic members 5 29—29, which members, to give them the required rigidity and effect a regular slide movement thereof on the coacting members 26, are joined by a cross bar 30, as shown. Each of the frame members 29 has its upper 10 end pivotally joined with the adjacent side beams 11—11 of the carrier frame as at 31 and each of the lower members 26 is hinged at 32 to the pendent brackets 33—33 on the side base timbers 1—1. 15 At the upper end the members 26 carry guide sheaves 34 and at a suitable point below the said sheaves, bearings 26^a—26^a are provided for the cross shaft 35 which carries a winding drum 36 and a large gear 37 at one 20 end, said members 26—26 also having bearings 38 for a power shaft 39 that carries a small gear 40 that meshes with the gear 37, and the shaft 39 has its ends projected and formed to receive winding cranks 41, as 25 shown.

42—42 designate a pair of lifting ropes which are connected at one end to their respective winding drums 36 and pass over the sheaves 34—34 connected with the cross 30 member 30 that joins the upper telescopic frame members, the said rope drive devices being so arranged that by manipulating the cranks 41, the hinged carrier frame or support can be raised or lowered and at the same 35 time swung upon its pivots to suit the requirements for lowering or stacking.

From the foregoing, taken in connection with the accompanying drawings, it is believed the complete construction, manner of 40 operation and advantages of my invention will be readily apparent.

It will be noticed that in the form of my invention so far described, the upper or delivery face of the stacker is at all times free 45 from obstructions or projections, thereby providing for a free and uninterrupted conveying of the sacks or other packages up through the delivery end of the frame and, furthermore, the elevating or lowering of the 50 said frame can be conveniently and expeditiously effected to suit the various heights of the bulks or packages being stored without retarding the action of the conveyer or elevating means and at the same time permitting 55 the stacking of the material to a greater height than is possible where the sustaining frame for the upper end of the carrier frame extends above the said carrier. Furthermore, by reason of connecting the several 60 parts in the manner shown and described, at no time is it necessary to disconnect any of the members of the entire machine, which remain at their initially connected position as the working or stacking progresses, the telescopic members constantly adjusting them-

selves as the power is applied at the crank handles.

In Fig. 4, I have illustrated a somewhat modified form of my invention which embodies the same general characteristics of 70 what is shown in the preferred form, but in this latter form the carrier frame supporting means consists of a single up-right 50 at each side which is arranged at the lower end of the base frame to swing rearwardly with respect 75 thereto, and the upper ends of the said up-rights extend above the carrier frame centrally to provide a clear space between the endless carrier and the cross head or bar 52 that connects with the upper extremities of 80 the members 50. In this latter form, means are also provided for raising or lowering the carrier frame during the operation of conveying the material and such means consists of a shaft 53 mounted on the side beams 11—11 85 near their lower end, drums 54—54 mounted on the shaft 53 with which drive ropes 55 connect, the sheaves 56 on the upper end of the uprights 50 over which the said ropes 55 pass, the latter having their free ends secured 90 to the side beams 11 of the carrier frame near the upper end.

To detachably sustain the uprights 50 at their upright position, two brace rods 58 are pivotally connected to each of the bearings 95 50, near their upper end, the lower end 58^a of the said rods being detachably joined with apertured ears 59^a on the base frame. By loosening the rods 58, the carrier frame can be lowered to the required position to pass 100 under obstructions or through door ways.

In Fig. 5, I have shown a further modification of my invention and which is also embodied in the broad or generic form of my invention as disclosed in Fig. 1. 105

In the present modified construction, however, the telescopic supporting sections comprise the lower members 60—60 fixedly secured to the base frame of the machine and provided with vertical grooves 60^a on their 110 inner faces, which extend substantially the full length and the said lower sections 60 extend up to a supplemental horizontally disposed frame portion 62 which extends forwardly and forms the brace for the endless 115 carrier frame, which latter, in the present form of my invention, is made of two sections, the lower or fixedly held portion 64 and the upper portion 65 that is hinged to the part 64 at a point just in line with the supplemental 120 frame 62 and the said hinged portion 65 is adapted, when swung back to the position shown in dotted lines in Fig. 5 to rest flatwise upon the supplemental framing.

To provide for gradually lowering the 125 upper or hinged carrier frame portion 65, as well as for sustaining it at its different adjustments, the supporting members 66 are pivotally connected at their upper end to the carrier frame 65 and they support friction 130

rollers 68 at their lower ends which travel in the grooves 60^a in the members 60 and by reason thereof the said roller bearings form differential pivotal connections for the supporting member 66.

Having thus described my invention, what I claim and desire to secure by Letters Patent, is:—

1. In a portable elevator of the character described, the combination with a base frame, the said frame including opposite side bars, an endless carrier frame pivotally mounted on the front ends of the side bars, a pair of supports for the upper end of the carrier frame, each of the said supports consisting of telescopic members, one of which is pivotally connected to swing outwardly as the carrier frame is lowered, the upper ones of said supports being pivotally connected to the upper end of the carrier frame, brackets carrying pulleys connecting the upper ends of the lower telescopic members, lift cables connected to the lower ends of the upper telescopic members, a winding drum mounted on the lower telescopic members over which the ends of the lift cables wind, and means also mounted on the lower telescopic members for winding up the drum.
2. As an improvement in portable elevators, the combination with the main frame, said frame including lower horizontal side

bars 1 and upper side bars 62, the said side bars 62 forming a supplemental supporting frame; of an endless carrier and a frame therefor, the said carrier frame comprising a lower and an upper section, the latter being hingedly connected to the lower section, the lower section being pivotally mounted at its lower end in the outer extremities of the side bars 1—1 and having its upper ends supportable on the outer end of the supplemental supporting frame, driving means on the main frame connected with the lower end of the endless carrier, mechanism for supporting and adjusting the upper or hinged end of the carrier, which comprises two sets of lower and upper telescopic members, the upper one for each set of members having a vertically slidable fulcrum connection with its co-acting lower member, the said upper members having pivotally connected to the upper end of the uppermost portion of the carrier frame, and means mounted on the lower telescopic members and the main frame for raising the upper telescopic members, and said means including lift cables connected to the fulcrum ends of the said upper telescopic members, as set forth.

EDWARD HANAK.
